UNITED STATES PATENT OFFICE

ELMER V. GMEINER, OF KNOXVILLE, TENNESSEE, ASSIGNOR TO DOHERTY RESEARCH COMPANY, OF NEW YORK, N. Y., A CORPORATION OF DELAWARE

DEVICE FOR SPREADING LIQUID

Application filed October 21, 1925. Serial No. 63,844.

This invention relates to improvements in liquid spreading or spraying devices and more particularly to a device which will rotate under the action of the hydrostatic head of 5 the liquid to be spread.

It is an object of the invention to provide a rotatable liquid-spreading device which will rotate under a low hydrostatic head of liquid.

Another object is to provide a liquid-spreading device which will distribute the liquid uniformly as the device rotates.

A still further object is to provide a liquid-spreading device which shall have auxiliary means enabling the liquid to impart rotation to the device when the volume of the liquid being supplied to the device is comparatively small.

The above and other objects of the invention will appear from the detailed description taken in connection with the accompanying drawings forming part of the specification.

Referring to the drawings:

Fig. 1 is an elevational view of the improved liquid-spreading device showing, the manner of supporting the same for rotation, and the mounting in the top of a tank with 25 in which the device is designed to be used;

Fig. 2 is a vertical section of the spreading device on an enlarged scale taken along the line 2—2 of Fig. 1 and showing certain preferred features of construction;

Fig. 3 is a partial plan and sectional view 35 on enlarged scale of the device, a portion of a radial branch of the same being broken away;

Fig. 4 is a perspective view on an enlarged scale of a portion of one of the radial branches 40 of the spreading device and showing the preferred manner of constructing the same;

Fig. 5 is a bottom plan view on an enlarged scale of a plate constituting the bottom of the casing; and

Fig. 6 is a detailed view on an enlarged

scale of the bearing from which the device is rotatively supported.

In the drawings, numeral 10 indicates a tube or stem to the lower end of which is secured a plurality of radially extending 50 liquid-spreading devices generally indicated at 12. The body of the device is preferably an elongated conduit or casing 14 having an opening at its top mid-way its ends, the tube or stem 10 being connected to the casing in line with said central opening. The bottom of the casing preferably takes the form illustrated in Fig. 5, the same consisting of a plate 16 suitably secured to the sides of the casing. This plate, on opposite sides of its center, is somewhat wider than the casing 14 to form shelves 18 for a purpose that will 55 presently appear. These shelves extend forwardly lengthwise of one of the casing walls on opposite sides of the center of the same, that is to say on diametrically opposite sides of the casing, both sides of the casing beyond which the shelves extend having a portion 60 cutaway as indicated at 20 to permit liquid to flow from the casing over the shelves. The plate 16 is provided with longitudinally extending and oppositely disposed downturned flanges 21, Fig. 2, to enable the plate to be secured to the side walls of the casing which 65 are not cutaway,—suitable securing means 70 passing through the flanges and adjacent sides of the casing holding the plate in fixed relation with respect to the casing 14. The ends of the plate 16 are also provided with 75 downturned flanges 24, Fig. 4, which are secured to the end walls 26 of the casing by any 80 suitable securing means generally indicated at 28.

Inasmuch as both of the radially extending branches 12 of the device are constructed in the same manner, a description of one will suffice for both. Extending between the top and bottom of the casing 14 in each of said branches is a plate or wall 30, Figs. 90 3 and 4, having a series of spaced openings

32 therein. This wall extends at an angle to the sides of the casing in such a manner that a channel of gradually decreasing width is formed, the channel being widest at the point where the liquid to be spread enters the casing, namely, where the stem or tube 10 connects with the casing, and is narrowest at the outer extremity of the branch. Liquid flows from the tube 10 into said channel and passes out over the shelf 18 through the ports 32 in the wall 30 and imparts a rotation to the device on the same principle as in the Barkers mill. By arranging the wall 30 at an angle the liquid will pass through all of the openings 32 in substantial quantities due to the fact that the gradually decreasing size of the channel prevents centrifugal force from moving a disproportionate amount of water toward the end of the branch. The bottom of the openings 32 preferably terminate above the bottom plate 16 a sufficient distance to permit liquid to flow toward the outer end of the branch in a trough-like channel.

25 By providing a shelf on which the liquid is received after passing through the openings 32 in the wall 30, the liquid will be spread in a thin sheet as it leaves the shelf under the rotation of the device.

30 In order to prevent the liquid on the shelf 18 from being moved by centrifugal force toward the outer extremity of the branch, there is preferably provided on the shelf a series of ribs 36, Fig. 4, which extend from the edge of the shelf 18 toward the wall 30. 35 There are also provided upright webs or baffles 38 which extend from the wall 30 forwardly to the casing wall having the cut-away portion 20. For convenience of construction, the baffles 36 and ribs 38 may conveniently be made in one piece as clearly indicated in Fig. 4.

That wall of the casing having the cut-away portion 20 is preferably provided with a vertically adjustable plate 40, the plate being provided with upright slots 42 through which extend headed screws 44 for guiding and holding the plate in adjusted position. Slots 42 are of sufficient width to enable the plate to be adjusted at an angle with respect to the shelf 18. By adjusting the plate 40 with respect to the shelf 18, the flow of liquid over the shelf is readily regulated.

In order that the device may function under heads of liquid which may be too low to operate the device already described, there is provided on each branch 12, an attachment consisting of a downwardly extending plate 46, the lower end of the plate being curved outwardly away from the shelf 18, the curve preferably being that of a cycloid. The upper edge of the plate 46, Figs. 2 and 4, is substantially in line with the outer edge of the shelf 18, the plate being secured to the casing in any suitable manner as by means of

a lateral flange 50 on the plate which extends below and is suitably secured to the shelf. Some of the liquid passing over the shelf 18 will drop onto the downwardly extending plate 46 and upon reaching the lower curved end thereof will impart an impelling action to the device as it leaves the plate. The plate 46 preferably depends from the shelf 18 at a slight angle to the vertical or to the axis of the tube 10 in order that advantage may be taken of the reaction set up between the plate and the falling water, such reaction tending to impart a rotary motion to the device about the axis of the tube 10. 70 75

In order to prevent the liquid which passes down the plate 46 from being moved outwardly by centrifugal force as the device rotates there is preferably provided a series of vertical baffles 58, Figs. 2 and 4, which extend from the top of the plate 46 to the bottom thereof. These baffles, for convenience of construction, are preferably of the form indicated in the drawings but it is within the spirit of the invention to make them of uniform height throughout. The baffles also tend to prevent buckling of the plate 46 which, it may be stated, will be made from thin material as will other parts of the device in order to keep the weight of the device as low as possible. Extending between the plate 46 and the bottom of the casing are suitable braces 52 which serve to maintain the plate in a fixed angular relation with respect to the shelf 18.

The tube or stem 10 telescopes a pipe 54 through which liquid is supplied to the liquid spreading device. This pipe 54 is shown as passing through a plate 56 which is the top of a tank within which the device is adapted to operate. Leading from the pipe 54 is a lateral branch 57 leading to a suitable source of liquid. At the top of the pipe 54 is arranged a thrust bearing generally indicated at 60 which co-operates with a rod 62 for supporting the rotary device in operative position with respect to the pipe 54. The rod 62 extends from the bearing 60 downwardly through the pipe 54 and through the tube or stem 10 and through the casing, the lower end of the rod being secured to the bottom of the casing in any suitable manner as shown in detail in Fig. 2. The top of the rod extends above the bearing 60 and is provided with a radially extending pointer or indicator 64 so that an observer may readily see if the device is rotating properly under the action of the liquid flowing thereto. The bearing is illustrated in detail in Fig. 6 and comprises among other things, a reducer 66 which is screwed to the top of pipe 54. In the top of the reducer is screwed a fitting 68 having a counter-bored portion 70 within which is mounted a suitable ball bearing 72. Resting on the ball bearing is a thrust bearing or cap 74 through which the rod 62 passes and to

which it is secured in any suitable manner as by means of a set screw 76 passing through the cap member 74.

The top of the tube 10 is preferably provided with a bearing ring 78 and the inside of the pipe 54 near its lower end is preferably provided with a bearing ring in the nature of a spider 80 through which the rod 62 passes. By providing these bearings the friction between the two pipes or conduits 10 and 54 is reduced to minimum.

The device has been primarily designed for spraying water in a gas scrubber but it is not limited to such use as will be readily appreciated.

While the invention has been described with considerable particularity of detail it is to be distinctly understood that no limitations are intended except as may be defined in the appended claims.

Having described my invention, what I claim is:

1. In a device for spreading liquid, an elongated liquid-discharging conduit having outlet ports throughout its length arranged to discharge liquid transversely of its longitudinal axis, said conduit being rotatable about an upright axis and having a tapered cross section offering a progressively increasing resistance to the flow of liquid toward the outer end of the conduit as it rotates about said axis, and means forming an elongated angular opening of adjustable area through which the liquid is finally discharged from the device.

2. In a device for spreading liquid, an elongated liquid-discharging conduit having outlet ports throughout its length, said conduit being rotatable about an upright axis and having a tapered cross section offering a progressively increasing resistance to the flow of liquid toward the outer end of the conduit as it rotates about said axis, and a plate depending from the conduit throughout its length below said ports and having its lower end dished outwardly and downwardly whereby liquid discharged from the conduit upon impinging on said dished surface will impart a lateral thrust tendency to rotate the device about said axis.

3. A rotary device for spreading liquid comprising a tube adapted to be rotated about its axis and through which the liquid to be spread is passed, a conduit extending radially from said tube, said conduit gradually decreasing in transverse width from the tube outwardly, a shelf extending from the bottom of the conduit, ports in the rear face of the conduit opening onto the shelf, webs extending upwardly from the shelf between the ports, and a plate extending downwardly from the edge of the shelf and having an outwardly curved lower end, whereby liquid discharged from said conduit and re-

ceived on the plate will impart a rotary impulse to the device about the tube axis.

4. A rotary device for spreading liquid comprising a tube adapted to be rotated about its axis and through which the liquid to be spread is passed, a conduit extending radially from said tube, said conduit gradually decreasing in transverse width from the tube outwardly, a shelf extending from the bottom of the conduit, ports in the conduit opening onto the shelf, webs extending upwardly from the shelf between the ports, a plate extending downwardly from the edge of the shelf and having an outwardly curved lower end, whereby liquid discharged from the conduit and received on the plate will impart a rotary impulse to the device about the tube axis, and means on the shelf and plate forming channels in which the liquid may flow.

5. In a device for spreading liquid, an elongated liquid-discharging conduit provided with means to discharge the liquid transversely of its length, said conduit being rotatable around an upright axis and gradually decreasing in cross-sectional area from its inlet outwardly whereby progressively increasing resistance is offered to the centrifugal force tending to move the liquid toward the outer end of the conduit as the latter moves around said axis, a shelf extending rearwardly thereof on which all of the discharged liquid from the conduit is received, and means forming with the upper surface of the shelf a relatively narrow elongated opening of adjustable area and dimensions through which the discharged liquid finally passes.

6. In a device for spreading liquid, an elongated liquid-discharging conduit having outlet ports arranged to discharge the liquid transversely of its length, said conduit being rotatable around an upright axis and gradually decreasing in cross-sectional area from its inlet outwardly whereby progressively increasing resistance is offered to the centrifugal force tending to move the liquid toward the outer end of the conduit as the latter moves around said axis, a shelf extending rearwardly thereof on which all of the discharged liquid from the conduit is received, and means forming with the upper surface of the shelf a relatively narrow elongated opening through which the discharged liquid finally passes, said means being vertically adjustable with respect to the surface of said shelf.

7. In a device for spreading liquid, an elongated liquid-discharging conduit having outlet ports arranged to discharge the liquid transversely of its length, said conduit being rotatable around an upright axis and gradually decreasing in cross-sectional area from its inlet outwardly whereby progressively increasing resistance is offered to the centrif-

ugal force tending to move the liquid toward the outer end of the conduit as the latter moves around said axis, a shelf extending rearwardly thereof on which all of the discharged liquid from the conduit is received, means forming with the upper surface of the shelf a relatively narrow elongated opening through which the discharged liquid passes, said means being vertically adjustable with respect to the surface of said shelf, and spaced upright webs on the shelf extending from the rear face of the conduit toward said opening.

In testimony whereof I affix my signature.

ELMER V. GMEINER.
